UNITED STATES PATENT OFFICE.

CHARLES A. RANDALL, OF NEW YORK, N. Y.

ELECTRICAL TIME-STAMP.

SPECIFICATION forming part of Letters Patent No. 380,594, dated April 3, 1888.

Application filed August 19, 1886. Renewed March 3, 1888. Serial No. 266,106. (No model.)

To all whom it may concern:

Be it known that I, CHARLES A. RANDALL, a citizen of the United States, residing at New York, in the county of New York and State 5 of New York, have invented new and useful Improvements in Electro-Mechanical Time-Printing Stamps, of which the following is a specification.

This invention relates to what are technically known as "time-printing stamps."

In instruments of this class using type-wheels it has been customary heretofore to drive one or more of the time-wheels by a clock-motor, the time-wheels being geared directly to the minute or hour shaft of the clock, and also to drive the time-wheels indirectly by a clock-motor, the power of the clock-motor being used to wind up or put tension upon a spring, which, being released at regular intervals by proper cams, ratchets, and detents, serves to turn the time-wheels; and, furthermore, it has been proposed to use two or more clock movements or motors geared or connected together, one acting to regulate or control the action of the other, one movement being used as a time-keeper and the other for the purpose of driving or rotating the time-wheels.

Electro-magnetic devices have also been employed for driving the printing-wheels of a time-stamp, and in such instance a ratchet-wheel co-operates with a lever carrying a pawl or dog which engages with the ratchet-wheel, the pawl-carrying lever being actuated by an electro-magnet and its armature, the printing in such type of stamp being effected by an electro-magnet.

All the devices above referred to are expensive, complicated, and, at least when using clock-motors, delicate, limited in power, and unreliable, and limited in the number of time, dating, and character wheels, and in many cases unreliable as to time, especially when the time-keeper is not detached from the stamp proper, the act of stamping or taking an impression causing a jarring of the clock, derangement of the parts, loss of time, and not infrequently the stopping entirely of the time-keeper.

It is the object of my invention to overcome the many serious defects in stamps of the class mentioned and to produce an instrument that shall be detached from the time-keeper, that

shall not be limited in power, and that shall be compact, simple, reliable, and otherwise adapted to the demands of business for which 55 it is intended; and to this end my invention consists in the construction and combination of devices hereinafter claimed.

In the drawings, Figure 1 is a plan view of a time-stamp with its top plate and inking devices removed. Fig. 2 is a side elevation of the stamp with its vertical wall removed and other parts broken away to expose operative parts. Fig. 3 is a top view showing the main and auxiliary impression levers and pads. 65 Fig. 4 is a side view of the minute-printing wheel and its driving spur-wheel. Fig. 5 is a detail view of the printing-wheel bearing words or symbols, the latter being on the periphery of the wheel. Fig. 6 is a detail view 70 of the electro-magnet and revolving armature of the electromotor. Fig. 7 is a diagram of an electric circuit including a battery and stamps controlled by a single-circuit wheel of a clock-movement; Fig. 8, a diagram of impression from the printing-wheels. Figs. 9, 10, and 11 are detail views.

The reference-numeral 1 designates a box or case consisting of side and end walls and top and bottom plates. A shaft, 2, passes transversely through this box or case and is secured in the side walls thereof. This shaft bears the various wheels concerned in the operation of printing, and it also bears other wheels for driving these printing-wheels. The 80 different wheels are loosely fitted on the shaft 2, so that they can turn thereon. The wheel 3 has its periphery divided into sixty parts and it bears numerals from 1 to 60 for printing the minutes. Secured to this wheel and moving with it is a spur-disk, 4, having also sixty teeth and meshing into a corresponding gear-gear wheel, 5, which is secured to a shaft, 6, journaled in the side walls of the case or box and capable of turning in its bearings. A 85 wheel, 7, serves to print the hours, and it is for such purpose divided into twenty-four parts or teeth, having thereon, preferably, the meridian-marks "A. M." and "P. M." and the numerals from 1 to 12 repeated. If desired, the letter "A." may be used for "A. M." and the letter "P." for "P. M." the type-wheel 90 then reading "A. 12," "A. 1," "A. 2," &c., and "P. 12," "P. 1," "P. 2," &c.

Secured to the type-wheel 7 and revolving with it is a gear-wheel, 8, having twenty-four teeth. This wheel meshes into a spur-wheel, 9, also having twenty-four teeth and mounted 5 loosely upon the shaft 6. This shaft also bears a fixed projecting pin, 10, which serves to act upon the teeth of the gear-wheel 8 for turning the same. A wheel, 11, loosely mounted on the shaft 2, is termed the "day-wheel," and is 10 preferably divided into thirty-two parts. It bears the numerals from 1 to 31, representing the thirty-one days of the months, and carries also some word, as "Change," or the figure of an arrow or a space. Secured to this wheel 11 15 is the gear-wheel 12, having thirty-two teeth, into which the pin 13, fixed to the side of wheel 9, plays.

A wheel, 14, also loosely mounted on the shaft 2, is designated the "month-wheel," and 20 is divided into twelve parts and carries the names of the months or abbreviations thereof. This wheel may also be provided with suitable gearing and rotated one step per month; but preferably, for the sake of simplicity, it is operated 25 manually.

A wheel, 15, on the shaft 2 is designated the "year-wheel," and it is preferably divided into twelve parts, in the same way as the month-wheel. These two wheels—viz., the 30 month and year wheels—are locked together and held in place by means of a suitable pin, 16, which passes through the side wall of the box 1 and enters suitable holes made in the wheels 14 and 15, as is seen in Fig. 1. These 35 holes are arranged in a circle, and they are made to register or correspond, as will be shown, and there are as many holes in the wheel as there are divisions or printing spaces thereon.

40 The day-wheel 11 is held in place or is prevented from turning, except at the proper time, by means of a spring-catch, 18, which bears in and upon the spur-wheel 12, fixed upon said day-wheel. The hour-wheel 7 also 45 may be held in a similar manner. The wheels 3, 4, and 5, on the contrary, are held by the motor device on the shaft 20 through the medium of the electro-magnet 21 and armature 24, the spring-catch 22, and the star-wheel

50 Referring to the motor device, it may be stated that it comprises an armature, 24, which is secured to the shaft 20 and revolves with it. This armature may be made of a single piece of cast-iron having six projecting teeth, as shown, or it may be made of a disk of wood carrying six or any other desired number of iron pieces, or it may be made in any other convenient manner, so long as it is operative 55 by the action of the electro-magnet 21.

60 The star-wheel 23, above referred to, is secured to the shaft 20, and to define its shape and function more precisely it may be stated that it has V-shaped teeth, upon which bears the spring-catch 22, which serves both to hold 65 the shaft and armature in place and to partly rotate it to a determined position. A pinion, 25, also secured to the shaft 20, meshes with

the main or large gear-wheel 5 on the shaft 6. As shown, the pinion must have six teeth or leaves to correspond to the six projections of 70 the armature; and since it meshes into the gear-wheel 5, having sixty teeth, it is obvious that the pinion and armature and shaft upon which they are mounted will revolve ten times to one of the wheel 5, or ten times an hour. 75

Upon the shaft 2, and preferably outside of the frame or box, I mount loosely one or more extra wheels, which are held in place by any suitable locking device—such as a pin, 27^a—passing through holes in the sides of the extra 80 wheels and entering the casing 1. The extra wheels (designated by the numerals 27 and 27^a) are divided into a certain number of points and carry thereon words, signs, and numerals.

The numeral-wheel 27^a I preferably divide 85 into thirty parts, carrying the ten digits and the numbers 5, 10, 15, 20, 25, 30, 35, 40, 45, 50, 55, 60, 65, 70, 75, 80, 85, 90, 95, 100.

The character, sign, or word wheel or wheels 27 may carry any conventional signs, words, 90 or characters for facilitating business, such as "Operator," "Rush," "Collect," "Paid," "Received," "Number of Words," &c. The word-wheel I preferably have print at right angles with the rotating time type-wheels an 95 impression reading something as shown in Fig. 8. These type-wheels may be constructed, in any of the well-known ways, of metal or wood and divided into teeth or parts and engraved with the letters, figures, or characters, 100 or they may be cast in metal or rubber; but, preferably, they are made of light metal covered on the circumference with a ring, band, or tire of soft rubber having the letters, numerals, &c., cast thereon. In Fig. 11 I have 105 shown such a rubber ring or tire with varied type, *a* designating the ring, and *b* the type.

Upon the inside of the box, case, or frame is secured the aforesaid electro-magnet 21, (or magnets,) having a rotary armature, 24. The 110 magnet 21 is included in an electric circuit with a battery and with the circuit-wheel 30 (shown in Fig. 7) or a similar one attached to or actuated by a time-keeper or clock-movement. The circuit-wheel may be made in any 115 of the well-known ways and secured to a shaft of the clock-movement or time-keeper and rotated thereby. The circuit-breaker must be provided with a proper number of contact-points to make the electromotor move the minute-wheel 3 one step each minute, and step by step, the circuit-wheel having, if secured to the hour-shaft of the clock-movement, sixty 120 makes and breaks, as shown in Fig. 10, so that the electro-magnet is charged and discharged 125 sixty times per hour.

As shown, the contact should be so made as to charge the electro-magnet sufficiently long to throw the armature, shaft, pinion, and V-shaped toothed wheel far enough to move the 130 V-shaped spring-catch 22 past and over one tooth, when, the circuit being broken, the magnet discharged, and the armature released, the spring-catch acts in and upon the V-shaped

toothed wheel, moving it to the correct position and holding it until the electro-magnet is again energized.

The impressions from the type-wheels may 5 be taken by a suitably supported impression-pad, either of the lever or plunger form. I have preferably used a lever, 35, as shown in Figs. 2 and 3, suitably fulcrumed and held normally in place by a spring and stop.

10 I also use, when desired, an auxiliary impression-lever, 36, so arranged that it may be used independently of or in conjunction with the main impression-lever. For this purpose I provide two levers, which are suitably fulcrumed, the auxiliary lever, as shown in Fig. 15 3, being in the path of the downward movement of the main lever to permit it to be caught by the projecting pin 37 and carried with it. This auxiliary lever is provided with a separate knot, so that it may be used independently, if desired.

The parts being made and arranged substantially as described, the operation is as follows: Commencing with a given time, the year, 25 month, day, and extra wheels being set correctly, and the hour and minute wheels being set to correspond with a time-keeper, when the circuit-wheel 30 at the time-keeper revolves, as soon as the circuit is closed, by contact of 30 the spring-contact 38 with a metal tooth of the circuit-wheel 30, a current of electricity is sent from the battery over the electro-magnet 21 of the electromotor, and the armature is actuated and the V-shaped toothed wheel moves one 35 tooth or thereabout, the shaft 20, shaft 6, pin 10, wheel 5, wheel 4, and minute-wheel 3 moving a corresponding distance to the proper positions, where they are held until the electromotor is again operated, and so on every minute. When the shaft 6 has made fifty-nine 40 sixtieths of a revolution, the pin 10 engages in the wheel 8, throwing the hour-wheel 7 one step at the complete revolution of the shaft 6, and also moving the wheel 9 by the action of 45 the spur-wheel 8 upon said wheel 9, and at twenty-four revolutions of the shaft 6 the hour-wheel 7 and gear-wheel 8 and gear-wheel 9 will have made one complete revolution, and the pin 13 upon the wheel 9, acting in and 50 upon the gear-wheel 12, will move it and the wheel 11 one step or one tooth at every revolution of the wheel 9, the gear-wheel 8, and the hour-wheel 7. It will be understood that in a similar manner the type-wheel 14 may be automatically set monthly and the type-wheel 15 55 once a year; but for simplicity I prefer to set these manually. An impression may be taken at any time from the type-wheels by a quick percussive-like blow of the impression-levers 60 35 36.

If extra impressions from the "extra" type-wheels are desired upon the same paper or document upon which a time-impression is made, or upon other papers or documents, it may be 65 done by means of the auxiliary lever 36 after setting the extra type-wheels for the required impressions.

In Fig. 7 I have shown the circuit-wheel of the time-keeper connected in circuit with a voltaic battery and three electro-magnets, 51 70 52 53, representing the electromotor of three distinct time-stamps, which it will be understood may be any reasonable distance from the time-keeper. This arrangement and use of time-stamps, located at different places and connected 75 in one or more electric circuits and controlled by a time-piece common to all, is especially valuable and advantageous for use by railroad and telegraph companies, manufacturers, and others requiring more than one time-stamp. 80 It will be seen that with this invention the stamp proper may be removed any reasonable distance from the time-keeper, thereby preventing any derangement of or interference with the time-keeper, insuring correct time-keeping, without which time-stamps are of 85 little or no value.

It will also be seen that with this invention ample power can be provided for actuating the parts and setting the type-wheels automatically and reliably; also, that the parts are reduced to a minimum, considering the needs of business, and also that with this invention any number of stamps may be automatically and simultaneously actuated and controlled by a 90 time-keeper or clock-movement common to all. While I have shown a single helix electromotor, I do not restrict myself thereto, as the electromotor may be made in many forms and with or without an escapement without 95 departing from the spirit of my invention.

While I have shown but one circuit-wheel, 30, and one circuit in Fig. 7, it will be understood that the time-keeper or clock-movement may be made to carry a number of circuit-wheels, or have a number of contact-springs bearing upon the circuit-wheel 30, and a corresponding number of circuits with a suitable battery for each. Any of the well-known devices may be employed for inking the type-wheels. It will be understood that the stamp, when constructed as shown, is more especially designed for use upon papers or documents having companies' or firms' names or business thereon. If, however, it is desirable to print 115 the name of the company, firm, or individual with the stamp, a fixed die may be readily arranged upon the top of the case or box, near to, parallel with, and in front and rear of the type-wheels. 120

What I claim is—

1. In a hand time-stamp, the combination, with a series of type-wheels and an impression pad or lever for taking impressions from said type-wheels, of an electric motor comprising an electro-magnet, a rotary armature, substantially as shown, and means, substantially as described, for partly rotating the armature to a determined position, intermediate gearing for driving the type-wheels, and a time-keeper or clock mechanism for controlling the action of the electric motor, substantially as herein set forth. 125

2. In a hand time-stamp, the combination,

with the type-wheels, the impression-pad, the electromotor for rotating the type-wheels, and the clock-movement or time-keeper for controlling the electromotor, of auxiliary type-wheel or type-wheels and an auxiliary impression-pad, substantially as set forth.

3. In a time-stamp, the combination of the electromotor device consisting, essentially, of a revolving shaft, an armature having radial projections mounted on said shaft, means, substantially as described, for partly rotating the armature to a determined position, and an electro-magnet, with means, substantially as described, for communicating motion from the armature shaft to a series of type-wheels, a circuit-wheel, and a clock-movement controlling the circuit-wheel, substantially as set forth.

4. In a time-stamp, the combination of the

rotary shaft, the armature mounted thereon, 20 the star-wheel also fixed on said shaft, and the spring-catch acting upon the star-wheel, with an electro-magnet, clock-movement, circuit-wheel, and time-printing wheels, substantially as herein set forth.

5. In a time-stamp, the combination of the shaft 6, the pin 10, the gear-wheel 9, having pin 13, and the spur-wheel 5, with an electromotor acting upon the wheel 5, and type-wheels with spur-wheels co-operating with the wheel 9 and pins 10 and 13, substantially as set forth.

In testimony whereof I have affixed my signature in presence of two witnesses.

CHARLES A. RANDALL.

Witnesses:
